UNITED STATES PATENT OFFICE.

GOTTLIEB HOCHSTRASSER, OF CHICAGO, ILLINOIS.

DOUBLE-ACTING SPRING-HINGE.

No. 889,589.

Specification of Letters Patent.

Patented Dec. 25, 1906.

Application filed April 16, 1906. Serial No. 311,850.

To all whom it may concern:

Be it known that I, GOTTLIEB HOCHSTRASSER, a citizen of the United States, residing at Chicago, Maywood, in the county of Cook and State of Illinois, have invented certain new and useful Improvements in Double-Acting Spring-Hinges; and I do hereby declare the following to be a full, clear, and exact description of the invention, such as will enable others skilled in the art to which it appertains to make and use the same.

My invention relates to a novel construction in a double-acting spring-hinge, the object being to provide a simple and efficient device of this character by means of which sagging of the doors supported thereby due to a loss of tension in the springs is entirely avoided; and it consists in the features of construction and combinations of parts hereinabove fully described and claimed.

In the accompanying drawings, illustrating my invention, Figure 1 is a perspective view of a hinge constructed in accordance with my invention. Fig. 2 is a view in end elevation of one of the leaves thereof. Fig. 3 is a central vertical section on the line 3-3 of Fig. 2. Fig. 4 is a top plan view of one of said leaves or the bottom plan view of the other thereof. Fig. 5 is a central vertical longitudinal section of said hinge on the line 5-5 of Fig. 1. Fig. 6 is a detail perspective view of a collar employed. Fig. 7 is a detail perspective view of a key employed. Fig. 8 is a detail plan view of a tension-adjusting member employed. Fig. 9 is a plan view of another collar employed. Fig. 10 is a plan section of the hinge on the line 10-10 of Fig. 5.

My said hinge comprises two leaves A and B, both of which are identical in shape and size and each of which is provided at one of its extreme ends with what I will term a "long" flange C and adjacent its other end with what I will term a "short" flange D, said flanges being provided with openings disposed in vertical alinement with each other and which are adapted to register with similar openings in the flanges of the other leaf to receive a pin or shaft E, constituting the pivot upon which said leaves rotate. The body portion of each of said leaves is of greater thickness midway between than at its side edges and each is provided midway between said side edges with a longitudinal

slot F, extending almost the entire length of said portion. The inner walls of said slots F serve as stops, as will be hereinafter more fully described. In assembling the hinge the said leaves A and B are so relatively disposed that the short flange of each is disposed inwardly of and in surface contact with the long flange of the other, and on said pin or shaft E are disposed loosely two collars G and H, respectively in surface contact with said short flanges D of said members A and B. The said collar G is provided with a longitudinal slotted hub I, either of the recesses in which is adapted to receive and engage one end J of a spiral tension-spring K, the other end L of the latter being similarly received and engaged in the slotted hub M of a tension-adjusting member N, disposed on said shaft in surface contact with said collar H. The latter is provided in its upper face with an annular groove O and with radially-disposed recesses P in its periphery communicating with said groove O, the said recesses P being adapted to receive a key Q, provided at one end with a lateral projection or arm R, which is adapted to be received in said groove O and serves as a pivot on which said key turns. The said tension-adjusting member N is provided with radial slots S in its periphery at intervals, which are adapted to register with said recesses P and receive the free end portion of said key Q to lock the same against rotation relatively to said collar H. The said collars G and H are provided each with two diametrically oppositely disposed projections T, one face of each of which is radially disposed and diametrically flush with the corresponding face of the other thereof, said faces being opposite and disposed relatively to each other, and said radial faces of said collar G being in turn oppositely disposed relatively to the corresponding faces of the projections of said collar H. In each of said radially-disposed faces of said projections T a set-screw U is mounted, the head of which is preferably flat and of as large area relatively to said radial face as space will permit, said heads serving to relieve said radial faces of wear and enabling the hinge to be adjusted, as will be hereinafter more fully described. By means of said slot F each of said leaves has its body portion divided into two parts, the opposing faces of which are of

relatively great width. In each of said opposing faces, at opposite ends of the leaf immediately inwardly of said flanges C and D, I provide a lateral recess V, through which 5 one of said projections T of said collars G and H is adapted to pass when said leaves A and B are rotated relatively to each other. In turning said leaves relatively to each other in one direction one of said collars G and H will 10 be revolved therewith by reason of engagement of one of the side faces of the slot F therein with one of said projections T, the other of said collars being meanwhile held against rotation by the engagement of one 15 of its projections with the oppositely-disposed side face of the slot F in the other member, the other or free projection of each of said collars G and H being adapted to pass freely through one of said recesses V, disposed 20 in its path as said leaves are turned. In the said inner faces of each of said slots F of each member opposite the lateral recess V in the opposite face of said slot I mount a set-screw 25 W, upon the head of which the heads of set-screws U are adapted, respectively, to bear, said set-screws W being adapted to relieve the faces of said slots of wear.

When the hinge is assembled, the said spring K is slack and said key Q will be in 30 the position indicated in dotted lines in Fig. 6. Primarily said spring must be brought to the tension necessary to swing the door, such tension depending upon the width and weight of the door. This is effected by rotating the said member N relatively to said collar and in a direction opposite to the direction in which said collar H is normally held 35 against revolution. Any suitable tool may be employed for this purpose, and when the 40 desired tension has been imparted to said spring K said key Q is forced at its free end into one of said slots S in said member N and the latter thus locked against movement relatively to said collar H. Where very light 45 doors are employed, the tension of said spring K may be rendered greater than desirable when said member N is turned through an arc equal to the distance between two adjacent recesses S and may be too slack unless 50 turned through an arc less than the aforesaid. In the latter event any slack may be taken up by adjusting said set-screws U and W, as will be obvious. The latter are more particularly adapted, however, to correct 55 any slight inclination laterally of said hinge when mounted, which inclination would act to cause said door to normally raise slightly to either side of its normal position, and this obviously would be objectionable. It will be 60 noted that in my said hinge the sole function of the spring is to maintain the door normally between the limits of its movement,

but does not in any manner carry any part of the weight of said door, the latter being carried entirely by said flanges C and D and said 65 pin or shaft E.

I claim as my invention—

1. A double-acting spring-hinge, comprising two uniform leaves each provided at and adjacent its opposite ends with flanges, said flanges of one leaf being adapted when said leaves are relatively inverted to rest upon the flanges of the other leaf, a shaft passing through all of said flanges to pivotally secure 70 said leaves to each other, disks disposed on said shaft, radial projections on said disks, stops disposed on said leaves in the path of the said projections, the stops disposed in the path of the projections of one of said disks being oppositely disposed relatively to 75 the stops in the path of the projections of the other disk, and a spring disposed in operative relation to said disks to normally maintain the same at the limits of their movement determined by said stops. 85

2. A double-acting spring-hinge, comprising two uniform leaves each provided at and adjacent its opposite ends with flanges, said flanges of one leaf being adapted when said leaves are relatively inverted to rest upon the flanges of the other leaf, a shaft passing through all of said flanges to pivotally secure 90 said leaves to each other, disks disposed on said shaft, radial projections on said disks, stops disposed on said leaves in the path of the said projections, the stops disposed in the path of the projections of one of said disks being oppositely disposed relatively to the 95 stops in the path of the projections of the other disk, and a spring disposed in operative relation to said disks to normally maintain the same at the limits of their movement determined by said stops, and set-screws disposed in the meeting faces of said projections and said stops to relieve the same of wear 100 and permit relative adjustment of the limits of movement of said disks. 105

3. A double-acting spring-hinge comprising two uniform leaves each provided at and adjacent its opposite ends with flanges, said flanges of one leaf being adapted when said leaves are relatively inverted to rest upon the flanges of the other leaf, a shaft passing through all of said flanges to pivotally secure 110 said leaves to each other, disks disposed on said shaft, radial projections on said disks, stops disposed on said leaves in the path of the said projections, the stops disposed in the path of the projections of one of said disks being oppositely disposed relatively to the 115 stops in the path of the projections of the other disk, a wheel provided with peripheral recesses disposed on said shaft adjacent one of said disks, the latter being provided with a 120

recess in its upper face and a radial recess communicating therewith, a key disposed in said radial recess, a projection on said key entering said recess in the upper face of said disk and forming a pivot upon which said key turns, said key being adapted to enter said peripheral recesses in said wheel to lock the latter against rotation relatively to said disk, and a spring disposed between said wheel and

the other of said disks and connected at its ends therewith.

In testimony whereof I have signed my name in presence of two subscribing witnesses.

GOTTLIEB HOCHSTRASSER.
